UNITED STATES PATENT OFFICE.

WILLIAM F. HAACK, OF BERWYN, ILLINOIS.

LEAD PENCIL.

Application filed January 12, 1922. Serial No. 528,801.

To all whom it may concern:

Be it known that I, WILLIAM F. HAACK, a citizen of the United States, residing at Berwyn, in the county of Cook and State of Illinois, have invented certain new and useful Improvements in Lead Pencils, of which the following is a specification.

This invention relates to lead pencils of the magazine type, which contain a central chamber in which the working lead is held and through which it is advanced by a plunger or pusher as the point of the lead wears away, and a magazine containing additional leads which are successively supplied, as required, to the central chamber.

One object of the invention is to provide a pencil of this type wherein the reserve leads may be supplied to the central or working chamber by simple relative movement of parts of the pencil and without requiring preliminary separation of the parts in order to introduce a reserve lead into the working chamber.

Another object of the invention is to provide a pencil of this character wherein the reserve leads may be introduced to the working chamber from the magazine by first turning the working chamber relatively to the magazine to allow a lead to drop out of the latter and then tilting the pencil to approximately horizontal position to cause the lead to fall into the working chamber through a lateral slot in the latter.

A further object is to provide a pencil of this character with a diaphanous or translucent shell which makes the interior parts visible and thus facilitates the proper manipulation of the relatively movable parts to effect the transfer of the leads from the magazine to the working chamber.

Other objects and attendant advantages of the invention will be apparent to persons skilled in the art as same becomes better understood by reference to the following detailed description, taken in connection with the accompanying drawing wherein I have illustrated one practical and workable embodiment of the invention and in which,—

Fig. 1 is a longitudinal axial section, showing the plunger or pusher at its maximum point of advancement;

Fig. 2 is a view similar to Fig. 1, but showing the plunger or pusher fully withdrawn, and one of the reserve leads from the magazine advancing into the working chamber;

Figs. 3, 4 and 5 are cross sections taken on the lines 3—3, 4—4 and 5—5, respectively, of Fig. 1; and

Fig. 6 is a fragmentary longitudinal section of the lower end of the working chamber and the surrounding metal tip or ferrule, showing the position of the lead retaining spring in the empty working chamber.

Referring to the drawing, B designates the cylindrical body or shell of the pencil, which is made of any suitable diaphanous or translucent material which will enable the interior parts to be observed through the same. Within approximately the upper half of the shell B is mounted a stationary compartmental magazine A, which may be conveniently formed by sheet metal bent into the corrugated cylindrical form illustrated in Fig. 3, each of the longitudinal corrugations constituting a chamber to hold a reserve lead C. The magazine A fits the shell B sufficiently tightly to be held stationary relatively to the latter, and at its lower end the magazine is stepped upon a valve disc Q, which latter is formed with a single eccentric slot or hole Q' (Fig. 2) through which the leads C may drop, one at a time, out of the magazine.

Rotatably fitted on the lower end of the shell B is a metal ferrule E having a downwardly tapered lower portion, within the tip of which is secured by soldering or otherwise the lower portion D' of a longitudinally split tube D, which forms the working or propulsion chamber of the pencil. This working chamber may also be formed from a strip of sheet metal the inner and longer portion D being bent to a generally V-form, as best shown in Fig. 4, with its longitudinal margins folded inwardly, and the outer and shorter portion D' being narrower and substantially circular in cross section, with a single longitudinal slot. The working chamber D is centered and held in proper relation to the shell by being attached at its upper end to the disc Q and at its lower end to a similar disc G which fits within the ferrule E and lies against the lower end of the shell B.

Frictionally mounted on the lower portion D' of the working chamber is a spring collar R, depending from which is a leaf spring R' that, when the working chamber is empty, springs through the narrow slot in the lower end of the latter and closes the same as clearly shown in Fig. 6. When,

however, the lead is forced downward through the working chamber, its point J forces the spring R' outwardly, and the latter, by reason of its frictional grip or drag on the lead prevents the latter from falling out of the pencil.

H designates a plunger or pusher having at its upper end a short spiral H' that cooperates with a tube K formed with an internal spiral or screw thread fitting spiral H' of the plunger. The upper end of the spiral tube K is united to a cap L sleeved on the body or shell B by being soldered to the latter at O, and centered and supported 15 by a disc or spider M.

The cap L is longitudinally slotted at diametrically opposite points, as shown at L' in Fig. 2, to permit its application and withdrawal.

20 Near its lower end the plunger H is formed with a pair of lateral lugs S (Figs. 2 and 4) which, by contact with the side walls of the working chamber D, hold the plunger against rotation on its longitudinal axis when the cap L and spiral tube K are rotated to advance or retract the plunger. The lower end of the plunger is also provided with a depending finger P which, after the lead has dropped into the working 25 chamber and is fully centered within the latter, overlaps the upper end of the lead and prevents it from tilting out of engagement with the plunger.

Fig. 1 shows the pencil with the working 30 lead advanced to the extreme position to which it can be forced by the plunger. At this stage, the plunger is fully retracted, by turning the cap L, to the position shown in Fig. 2. With the shell held in one hand 35 and the metal tip or ferrule E in the other, these parts are relatively rotated until the hole or slot Q' registers with the lower end of a magazine chamber containing a reserve lead. With the pencil held vertical, or 40 slightly tilted from vertical, the lead drops with its lower end entering the working chamber, as shown in Fig. 2, until its lower end strikes the upper end of the fragment of the previous lead within the tip portion 45 D' of the working chamber. By then tilting the pencil to approximately horizontal position, the upper end of the new lead drops into the central channel of the working chamber, whereupon the cap L is then 50 turned to bring the plunger down onto the upper end of the new lead, with the finger P locking the latter against lateral displacement. The cap L is then turned from time to time to feed the new lead and the fragment of the previous lead forwardly as the 55 leads are gradually worn away in use.

A leading advantage of my present invention resides in the translucent character of the shell, in combination with a working chamber and a magazine within the latter

so co-ordinated and related that, under a relative turning movement, a reserve lead can be fed from the magazine to the working chamber, the manipulation of the parts being observable through the translucent shell. Manifestly the specific details herein shown and described for purposes of illustration may be variously modified without altering the substantial character of the invention or sacrificing any of the advantages thereof. Hence, I reserve all such variations and modifications as fall within the spirit and purview of the appended claims.

I claim:—

1. In a magazine pencil, the combination of a diaphanous shell, a magazine for leads occupying approximately one longitudinal half of said shell, a working chamber coaxial with said shell and disposed within the other longitudinal half of the latter and adapted to receive the leads successively from said magazine under a relative rotary movement of said magazine and working chamber, and a plunger for forcing the lead endwise through said working chamber.

2. In a magazine lead pencil, the combination of a diaphanous shell, a multi-cell magazine for leads mounted within the upper portion of said shell, a working chamber coaxial with said shell beneath said magazine and rotatable relatively to the latter, said working chamber having a longitudinal slot for the admission of a lead thereto, a valve carried by said working chamber and controlling the discharge of leads from said magazine, and a plunger for forcing the lead endwise through said working chamber.

3. In a magazine lead pencil, the combination of a diaphanous shell, an annular multi-cell magazine for leads mounted within the upper portion of said shell, a working chamber coaxial with said shell beneath said magazine and rotatable relatively to the latter, said working chamber having a longitudinal slot for the admission of a lead thereto, a valve disc carried by said working chamber and controlling the discharge of leads from said magazine, and a plunger for forcing the lead endwise through said working chamber, the forward end of said plunger having an offset depending finger for retaining the upper end of the lead in said working chamber.

4. In a magazine lead pencil, the combination of a shell, an angular multi-cell magazine for leads mounted within the upper portion of said shell, a working chamber coaxial with said shell beneath said magazine and rotatable relatively to the latter, said working chamber having a longitudinal slot for the admission of a lead thereto, a valve disc carried by said working chamber and controlling the discharge of leads from said magazine, a plunger for forcing the lead

endwise through said working chamber, said plunger having a spiral head, a rotatable tube mounted within said magazine and having an internal spiral engaged with the 5 head of said plunger for advancing and retracting the latter, and means for locking said plunger against turning movement.

5. In a magazine lead pencil, the combination of a shell, a multi-cell magazine for leads mounted within the upper portion of said shell, a working chamber coaxial with said shell beneath said magazine and formed with a longitudinal slot for the admission of a lead thereto, a ferrule rotatably mounted 10 on the lower end of said shell and formed with a pointed tip surrounding and attached to the lower end of said working chamber, a valve carried by the upper end of said working chamber and controlling the discharge of leads 15 from said magazine, a plunger for forcing the lead endwise through said working chamber, said plunger having a spiral head, a tube mounted within said magazine and having an internal spiral engaged with the 20 head of said plunger for advancing and retracting the latter, and means for locking said plunger against turning movement.

6. In a magazine lead pencil, the combi-

nation of a shell, an annular multi-cell magazine for leads mounted within the 25 upper portion of said shell, a working chamber coaxial with said shell beneath said magazine and formed with a longitudinal slot for the admission of a lead thereto, a ferrule rotatably mounted on the lower end 30 of said shell and formed with a pointed tip surrounding and attached to the lower end of said working chamber, a valve disc carried by the upper end of said working chamber and controlling the discharge of leads 35 from said magazine, a plunger for forcing the lead endwise through said working chamber, said plunger having a spiral head, a tube mounted within said magazine and having an internal spiral engaged with the 40 head of said plunger for advancing and retracting the latter, a cap rotatably mounted on the upper end of said shell and attached to said tube, and means for locking said plunger against turning movement.

WILLIAM F. HAACK
